UNITED STATES PATENT OFFICE.

FRANK E. DAVIS, OF BREMERTON, WASHINGTON.

SHADE FOR AUTO HEAD-LAMPS.

1,350,212.

Specification of Letters Patent. Patented Aug. 17, 1920.

Application filed October 31, 1919. Serial No. 334,717.

To all whom it may concern:

Be it known that I, FRANK E. DAVIS, a citizen of the United States, residing at Bremerton, in the county of Kitsap and 5 State of Washington, have invented new and useful Improvements in Shades for Auto Head-Lamps, of which the following is a specification.

This invention relates to automobile head 10 lamps and has for its object the provision of a shield attachment engageable upon a head lamp and provided with a plurality of vanes or fins so arranged as to prevent blinding of the drivers of approaching automobiles while yet permitting adequate illumination of the roadway.

An important object is the provision of a shield of this character which is detachably engageable upon a head lamp and which 20 is provided at its upper portion with a plurality of parallel vanes which extend downwardly in an inclined direction and which is provided at its lower portion with a plurality of vanes which are radial with 25 respect to the center of the source of light, that is they coincide in direction with the direction of the rays of light.

An additional object is the provision of a device of this character which will be simple 30 and inexpensive in manufacture, highly efficient and durable in use, efficient in service, and a general improvement in the art.

With the above and other objects and 35 advantages in view the invention consists in the details of construction to be herein-after more fully described and claimed and illustrated in the accompanying drawing in which—

40 Fig. 1 is a side elevation of a head lamp equipped with my device,

Fig. 2 is a front elevation, and

Fig. 3 is a vertical longitudinal sectional view.

45 Referring more particularly to the drawing, the letter A designates an automobile head lamp of ordinary construction having an incandescent bulb B as its source of light, though it will be understood that as far as 50 the invention is concerned, the source of light might be an acetylene gas burner.

In carrying out my invention, I provide a shield which comprises a circular band 10 of a size to engage against the front of 55 a lamp A and this band carries a plurality

of spring fingers 11 inwardly curved at their outer ends, as shown at 12, for engagement with the flange C usually provided on head lamps and often forming the door frame thereof.

Secured transversely of the upper portion of the band 10 are vanes or fins 13 which are parallel, as shown, and secured within the lower portion of the band are transversely disposed blades or fins 14. The vanes or fins 13 are inclined downwardly and forwardly so as to deflect light from said source B onto the roadway while not permitting the rays of light to extend upwardly. The vanes or blades 14 are also inclined downwardly except that instead of being parallel they are radial with respect to the center of the bulb B or the source of light. All these vanes are formed preferably of tin or other suitable thin material and are preferably 75 painted black upon their upper sides.

In the use of my shield it will be seen that rays of light emanating from the source B will strike against the blades or vanes 13 and be deflected thereby downwardly in 80 an inclined direction onto the roadway and the rays of light emanating from the source will pass directly between the various blades 14 while the rays of light emanating from the source and reflected from the reflector 85 of the lamp and projected forwardly will, upon striking the blades 14, be reflected downwardly. It will therefore be seen that the great disadvantage of the glaring of head lights, a feature prohibited by law in 90 most communities, will be eliminated while not in any way sacrificing efficient illumination of the roadway.

While I have shown and described the preferred embodiment of my invention it is 95 of course to be understood that I reserve the right to make such changes in the form, construction, and arrangement of parts as will not depart from the spirit of the invention or the scope of the subjoined claims. 100

Having thus described my invention, I claim:

1. An attachment for automobile head lamps comprising a circular band detachably engaged upon the front of a head lamp, a 105 plurality of transverse forwardly and downwardly inclined parallel blades within the upper portion of said band, and a plurality of other downwardly and forwardly inclined blades within the lower portion of 110

said band, said last named blades being radial with respect to the center of the source of light of the lamp.

2. A shield attachment for automobile head lamps comprising a circular band attachment engaged upon the front of the head lamp, a plurality of transverse forwardly and downwardly inclined parallel blades within the upper portion of said band, and a plurality of other downwardly

and forwardly inclined blades within the lower portion of said band, said last named blades being radial with respect to the center of the source of light of the lamp, said blades being painted black upon their upper ¹⁵ surfaces and having their under surfaces polished.

In testimony whereof I affix my signature.

FRANK E. DAVIS.
